UNITED STATES PATENT OFFICE.

WILLIAM J. MORRIN, OF NEW BRITAIN, CONNECTICUT.

REMOVABLE FLOORING FOR ELEVATOR-SHAFTS.

1,335,849.

Specification of Letters Patent.

Patented Apr. 6, 1920.

Application filed June 14, 1919. Serial No. 304,182.

To all whom it may concern:

Be it known that I, WILLIAM J. MORRIN, a citizen of the United States, residing in New Britain, county of Hartford, and State of Connecticut, have invented a new and useful Improvement in Removable Flooring for Elevator-Shafts, of which the following is a description.

This invention has reference to movable flooring for elevator shafts and, particularly, has reference to mechanism by which sections of the flooring of buildings may be lowered and shifted aside for the purpose of permitting the passage of elevators.

More particularly my invention relates to a means by which, in garages, for example, a section of the flooring is made movable in two directions at right-angles to each other for the purpose of raising and lowering an elevator through the space occupied by said flooring, and whereby, when the elevator is not in use, the section of flooring may be locked in position for ordinary traffic.

Among the objects of my invention may be noted the following: to provide a movable section for the floors of buildings which may be depressed a predetermined distance to make way for an elevator; to provide means by which a section of the flooring of buildings may be depressed a predetermined distance and then shifted laterally so as to provide a shaft or passage through which an elevator may be lowered and raised; to provide means by which an elevator may be caused to actuate mechanism for releasing a floor section whereby the latter may be depressed to make way for the elevator as the latter descends; to provide means by which an elevator may depress a floor section so as to occupy the space of said floor section, and by which, when the elevator is raised, the floor section will automatically return to its normal position; to provide means by which, when an elevator is depressed, a movable

floor section may be automatically depressed and may then be shifted laterally and locked in shifted position whereby to provide for the passage, in opposite directions, of an elevator; to provide means in a garage where floor space is restricted, whereby an elevator operating above the ground floor may be lowered to the ground floor and occupy the space previously occupied by a section of flooring automatically displaced upon the descent of the elevator; to provide a movable floor section for the ground floor of

garages, for example, which is normally flush with the ground floor, but which may be displaced automatically by an elevator which, in turn, occupies the position of the displaced floor section so as to have its surface flush with the ground floor for the passage of traffic; to provide means in a building of several stories, including a cellar, whereby a section of the ground floor, normally devoted to traffic, may be displaced and the space occupied by an elevator for traffic purposes, and which flooring may be shifted laterally to permit the descent of the elevator into the cellar, and which flooring may be subsequently returned to normal position after the elevator has been raised above the ground floor; and to provide simple, strong, durable and efficacious means for carrying out the foregoing objects.

With the above objects in view and others which will be detailed during the course of this description, my invention consists in the parts, features, elements and combinations thereof hereinafter described and claimed.

In order that my invention may be clearly understood, I have provided drawings wherein:

Figure 1 is a sectional elevation of a portion of a floor of a garage or other building showing the installation of my invention, including an elevator in juxtaposition such as to illustrate the mode of tripping the several locking mechanisms by which the movable floor section is locked in place;

Fig. 2 is an end elevation of the mechanism shown in Fig. 1, the section being substantially on the line 2—2 of Fig. 1, but omitting the lower locking mechanism, in order to avoid confusion;

Fig. 3 is a sectional elevation showing a detail, on an enlarged scale, of the locking and tripping mechanism actuated by the elevator as a preliminary to the depression of the movable floor section;

Fig. 4 is a top plan view on substantially the scale of Fig. 1 showing the movable floor section and the tripping mechanism carried thereby, in dotted lines;

Fig. 5 is a sectional elevation illustrating the means by which the movable flooring may be shifted laterally when depressed below the normal floor, and by which said flooring is locked and unlocked after being shifted;

Fig. 6 is an enlarged sectional view of the details of a locking and tripping mecha-

nism by which the movable flooring is locked to the counter-weight frame; and

Fig. 7 is a plan of the winding drums and shaft carrying the same by which the movable flooring is shifted laterally.

Primarily, it should be understood that my invention has been designed for use in automobile garages where the ground floor space is restricted, and every part of which is practically in demand at all times, and where it is not feasible to have an elevator shaft open, all or any material part of the time. According to my invention, a movable floor section is provided for the normal or ground floor of the building, which movable floor section is always in place and capable of sustaining traffic, excepting only when the elevator descends to take its place or to pass through the shaft in which it is located, in order to descend into the cellar or basement of the building for bringing up a load. Also, according to my invention, the movable floor section is shifted laterally away from the shaft by a manually operated means, for example, in order to clear the way for the passage of the elevator, which latter, on its return, and the return of the movable floor section, is caused to unlock the latter so that it may return to normal position, following the elevator, and be locked flush with the surrounding flooring of the building. From the foregoing brief statement of objects and design of my invention, the following detail description will be readily understood:

The numeral 1 indicates the normal garage floor, in which, in a sufficiently large space or shaft, is set the removable flooring, or section of flooring 2. The elevator is indicated by 3; 4 being the cables or lifts operated in any suitable manner. The bottom of the elevator, at its opposite ends, has rigidly secured thereto a tripping device 5, the upper end of which is bifurcated, Fig. 2, so as to embrace one of the longitudinal beams 6, to which it is bolted, as at 7, thus being held securely in place. One of the beams of the elevator, preferably the middle one 6, is also provided with a pivoted tripping device 8 adapted to be normally held out of operation alongside the beam, and adapted to be swung about its pivot 9 into the dotted line position shown in Fig. 1, and into engagement with a stop-pin 10, the tripping device being operated by a lug 11 fixed thereto and pivotally connected to a rod 12 the opposite end of which is suitably supported at one end of the elevator, and to which is connected a chain, or other flexible device 13, through the medium of which the rod may be drawn longitudinally, so as to swing the tripping device about its pivot into the dotted line position as stated. The two end tripping devices 5 operate through elongated slots 14 in the movable

section of flooring 2, and the middle tripping device operates through an elongated slot 15 in the said movable floor section.

The movable floor section is composed of a plurality of cross beams 16 and a plurality of longitudinal beams 17, all said beams being rigidly secured together at points of crossing in any suitable manner, and the first said beams having the flooring rigidly secured thereto. Beneath the movable floor section 2 is a counter-weight frame, composed of longitudinal and transverse beams 18, 19 rigidly secured together, which frame is rectangular in form and slightly larger than the movable floor section, and is mounted to travel on I-beams 20 rigidly secured to joists, girders or other substantial part 21 of the flooring 1 of the garage, by means of anti-frictional rolls or flanged wheels 22 mounted to rotate on axles 23 fixed in a pair of straps or retainers 24, rigidly secured to the timbers of the counter-weight frame. Alternatively, the straps or retainers 24 may afford journal bearings for the axles 23, and the wheels 22 may be rigidly secured to the latter. The movable floor section 2 is held in the position shown in Fig. 1 with its upper surface flush with the normal or ground floor of the garage by means of counter-weights 25, connected to cables 26 passing over pulleys 27 and secured to pendent bars 28 rigidly secured to beams of the floor section 2, the pulleys being journaled in the upper ends of standards 29 bolted to the counter-weight frame. Thus, the counter-weight frame is mounted to travel longitudinally on the I-beams 20 and the floor section 2 is sustained by the counter-weights and cables in normal position relatively to the counter-weight frame. In order to guide the movable floor section in its movement relatively to the counter-weight frame, and to prevent it from sagging relatively to said frame, dependent guide-bars 30 are rigidly secured to the bottom of the floor section 2 and are of such length as to normally enter, and stand within, borings or holes 31 in the counter-weight frame, said rods, when the floor is depressed, operating within said borings, thus overcoming any tendency of the movable flooring to sag or materially vibrate relatively to the counter-weight frame under the load imposed thereon.

To hold the movable floor section with its top surface flush with the normal surrounding floor, locking devices are provided, Figs. 1, 2 and 3, consisting of slidable bolts 32, secured to the bottom of beams of the movable flooring and adapted to normally rest upon brackets or latch-seats 33 secured to the girders or beams 34 of the normal flooring adjacent the shaft. The bolts are held to freely slide in brackets or straps 35 secured to the beams, as shown in Figs. 2 and 3.

3, and each has pivotally connected to it one end of a connecting rod or link 36, the other end of which is connected to the depending crank-arm 37 carried by a horizontal rock-shaft 38 extending longitudinally of the movable flooring and centrally thereof, a horizontal crank-arm 39 likewise carried by the rock-shaft 38 standing in position to be engaged by the end tripping devices 5. 10 Each of the connecting rods 36 has attached to it a coiled spring 40, one end of which is connected to the rod 36, and the other end of which is connected to a fixture, such as the beam 17 on which the bolt slides. The 15 crank-arms 37, 39 on the two shafts are set oppositely to each other and closely together, so that the horizontal arms normally stand in parallelism and in position to be engaged simultaneously by the tripping devices 5, which are made broad enough to engage 20 both arms at once. As shown in the drawings, Figs. 1 and 4, there are four sets of tripping devices, one pair of rock-shafts, four sets of crank-arms, springs, rods and 25 locking bolts arranged as shown in Fig. 4. Thus, the movable floor section is rigidly secured in place by four locking bolts on each of its longitudinal sides. I desire it understood, however, that my invention is 30 not limited to any precise number of locking bolts and actuating mechanisms, nor to the particular arrangement thereof shown in the drawings. Variations may be made to accord with local conditions and the size 35 of the movable flooring, and to secure strength and rigidity of the flooring when in place. Up to this point, means have been described whereby the movable floor section is held locked in a normal working position 40 with its top surface flush with the surrounding floor surface, thus giving continuity to the latter and an uninterrupted traction surface in the garage. The movable floor section is not only rigidly held in position by 45 the bolts; but, the counter-weights normally tend also to hold the floor section counterbalanced. When the elevator is lowered and the tripping devices engage the pairs of horizontal arms 30 on the rock-shafts 38, 50 the springs 40 are distended with a normal tendency to return the horizontal arms to normal position. When the tripping devices 5 depress the pairs of horizontal arms, the rods 36 and bolts 32 are shifted,—limited 55 by stops 41,—thus unseating the bolts and enabling the movable floor section to be depressed by engagement of the top surface thereof with the bottom surface of the elevator 3, the descent of the floor section 60 and elevator being simultaneous and guided by reason of the tripping devices descending through the apertures 14 in the floor section and the rods 30 passing through the guide borings 31 in the counter-weight frame. 65 As the elevator and floor section de-

scend, the counter-weights 25 are lifted. Thus the floor section is displaced by the elevator, and automatically tripped by the latter so that it may be displaced, and the elevator takes the position of the floor section 70 with its top surface flush with the surrounding normal floor surface of the garage or building. After the load has been either removed from, or placed upon, the elevator, the latter is drawn up by the usual mechanism, followed by the floor section until its 75 surface is flush with the surrounding normal floor of the garage, under the influence of the counter-weights. The elevator continues to rise, whereupon the tripping devices 80 release the horizontal arms, so that the springs attached to the connecting rods will shift said rods laterally, so as to force the bolts outwardly in position to engage the bolt-seats. Should the floor section lag relatively to the elevator, the arrangement is such that the elevator would release the arms and the bolts before the floor section reaches its normal position. Hence, the continued 85 rise of the floor section would cause the bolts 90 to be retracted by the bracket-seats until the latter were passed, whereupon the bolts would automatically shift and snap into locking position, as shown in Figs. 2 and 3. The mechanism so far described provides 95 for the depression of the floor section and for the elevator taking the place of the floor section, for traffic purposes on the floor of the garage. The floor section and counter-weight frame, together with all mechanisms 100 carried thereby, can also be shifted laterally under the normal floor of the garage to enable the elevator to descend to the cellar with a load or to get a load. To accomplish this, the mechanism shown in Figs. 5, 6 and 105 7 is provided, consisting of a sprocket and gear mechanism for shifting the movable floor section and counter-weight frame, and parts carried thereby, from the full line position to the dotted line position, Fig. 5. 110 Said mechanism comprises a standard or suitable support 42 erected on the normal floor of the garage, in which is journaled a stud-shaft carrying a gear 44 at one end and a bevel-pinion 45 at the other end. A 115 second bevel-pinion 46 meshes with the first bevel-pinion and is carried by a crank shaft, the handle 47 of which is manually operated. By rotating the handle, the stud shaft is rotated, which, in turn, operates the 120 gear 44 meshing with a similar gear carried by the shaft 48, suitably journaled in the upright or standard and carrying at its other end a sprocket wheel 49 around which extends a sprocket chain 50, and which latter 125 extends around and drives a second sprocket wheel 51, carried by a shaft 52 journaled in any suitable position, but preferably in the I-beams 20, or blocks connected therewith, and carrying at its opposite ends winding 130

4

drums 53. To the middle of the shaft 52 is secured the end of a cable 54, which, in turn, is adjustably secured to one side of the counter-weight framing 18 of the movable floor section as at 55. Another cable 56 is secured at its end to the same drum, and the opposite end of said cable is secured adjustably as at 57 to the counter-weight frame at its opposite side. The other drum has connected thereto in similar manner cables 58 59, the opposite ends of which are connected adjustably to the opposite sides of the counter-weight frame. Thus, by turning the crank-arm in one direction, 10 the movable flooring and counter-weight frame, and all parts carried thereby, can be shifted laterally into the dotted line position, Fig. 5, and by turning the crank in the opposite direction, said parts can be shifted laterally in reverse direction to the full line position, Fig. 5. Before the movable flooring and counter-weight frame have been shifted laterally, the movable flooring is locked to the counter-weight frame by bolts 15 similar to those which lock the movable flooring to the normal flooring, this locking mechanism being for the purpose of preventing the movable flooring, after being shifted laterally, from rising relatively to 20 the counter-weight frame into engagement with the beams or bottom of the normal flooring.

The locking mechanism consists of the horizontal crank-arms 60 carried by the 25 rock-shaft 61 in turn having the depending arms 62 pivotally connected by rods 63 to the locking bolts 64. Springs 65 control the rods 63 and have one end connected thereto, and the other end connected to a fixture of the counterweight framing, and the locking bolts 64 are carried by straps or 30 brackets 64^a on the bar 18 of the counter-weight framing. As the elevator descends, the tripping device 8, shifted into dotted 35 line position Fig. 1, at the proper time, passes through the aperture 15, engages the pair of arms 60, and shifts the bolts 64 inwardly thus releasing the movable flooring from the counterweight framing. The 40 bolts are automatically shifted inwardly when the movable flooring descends, since the locking brackets 66 are beveled on their underside so that the brackets engage and shift the bolts which automatically snap 45 into locking position shown in Fig. 6; but, the elevator must be employed to depress the floor section preparatory to locking the same to the counterweight frame, so that the two may be shifted laterally together. 50 Prior to shifting the movable flooring and counterweight frame laterally, the elevator is raised a short distance to remove the several tripping devices from the slots in the movable floor section, so that the latter can

be shifted laterally by the mechanism already described. Thus the elevator shaft is cleared and the elevator may descend into the basement without interference from the movable floor section and its counterweight frame. After getting or delivering its load, 55 the elevator may be raised to a position such that its tripping devices cannot be engaged by the movable floor section when the latter is shifted back to the position shown in full lines in Fig. 5. Then the 60 elevator is caused to descend again, so that the central tripping device, brought into position at this time as above described, may depress the horizontal arms 60 and thus shift the bolts 64 from their seats. Thus, 65 the movable floor section may rise with the elevator, as the latter rises, and, as the elevator leaves the movable floor section, the locking bolts of the latter will snap into place and thus hold the floor section rigidly 70 in position for traffic with its top surface flush with the surrounding normal garage floor surface. The shafts 61 may be journaled in bearings 67 mounted on the framing 18, and the bolts 64 may be mounted to 75 slide on blocks 68 on said framing.

The cables 54 and 58 may be passed about pulleys 54^a suitably mounted on brackets fixed to the flooring or joists thereof, this being merely a convenient disposition of the 80 long lengths of cables 54, 58 to control their slack. The locking mechanism carried by the counter-weight frame, and which cooperates with the movable floor section to hold the same depressed preparatory to 85 shifting the same laterally, is extended on the said counter-weight frame at a right-angle to the locking devices carried by the movable floor section, and which cooperates with the adjacent walls of the shaft in the 90 garage floor to lock the movable flooring flush with the garage floor. This is clearly shown in Fig. 1.

From the foregoing it will be seen that I have provided a simple, strong and effective 95 means by which a garage floor section can be automatically depressed to make way for positioning the elevator, for loading and unloading, and shifting laterally the floor section so as to clear the shaft for the further descent of the elevator to a cellar or 100 sub-cellars to receive or deliver a load.

Having thus described my invention, what I claim and desire to secure by Letters Patent is:

1. In combination with the flooring of a building used for traffic, a movable floor section capable of sustaining such traffic and movable to a limited extent to a position just below said flooring; mechanism for locking the movable floor section flush with the building flooring; means for tripping said locking mechanism; and means for de-

- pressing said movable floor section to the extent stated to make way for an elevator.
2. In combination with the flooring of a building used for traffic, a movable floor section capable of sustaining such traffic and movable to a limited extent to a position just below said flooring; mechanism for locking the movable floor section flush with the building flooring; an elevator mounted to operate above the movable floor section; and means carried by the elevator for tripping the locking mechanism whereby the floor section may be depressed to the extent stated to make way for the elevator.
3. In combination with the flooring of a building used for traffic, a movable floor section capable of sustaining such traffic; counterbalancing means for holding the floor section flush with the flooring; mechanism for locking the floor section in position; and means for tripping the locking mechanism whereby the floor section may be depressed to make way for an elevator.
4. In combination with the flooring of a building used for traffic, a movable floor section capable of sustaining such traffic and movable to a limited extent to a position just below said flooring; locking mechanism for holding the floor section flush with the flooring; an elevator mounted to operate above the floor section; and tripping means carried by the elevator for tripping the locking mechanism, said tripping means operating upon the descent of the elevator whereby the latter, when the locking mechanism is tripped, may depress the floor section to the extent stated and occupy the position of the latter with its surface flush with the flooring.
5. In combination with the flooring of a building, a movable floor section; mechanism for locking the floor section flush with the flooring; tripping means for tripping the locking mechanism whereby the floor section may be depressed; means for shifting the floor section laterally; and means for locking the floor section depressed preparatory to shifting the same laterally.
6. In combination with the flooring of a building having an elevator shaft therein, a movable floor section set within the elevator shaft; means for locking the floor section in said shaft; means for tripping the locking mechanism whereby the floor section may be depressed in said shaft; and means for shifting the floor section laterally whereby to clear said shaft.
7. In combination with the flooring of a building having an elevator shaft, a movable floor section located in said shaft; mechanism for locking the floor section in said shaft; an elevator operating above the floor section; means for tripping the locking mechanism whereby the flooring may be depressed as the elevator descends into the shaft; and means for shifting the floor section laterally to clear the shaft for the passage of the elevator.
8. In combination with the flooring of a building having an elevator shaft, a movable floor section; locking mechanism mounted on the bottom of said floor section to lock the latter in the shaft with its surface flush with the flooring; an elevator operating above the floor section; tripping means carried by the elevator for tripping the locking mechanism as the elevator descends, whereby, during the descent of the elevator, the floor section may be depressed; means whereby, as the floor section is depressed by the elevator, the floor section may be locked depressed; and means for shifting the floor section laterally after it has been locked in depressed position.
9. In combination with the flooring of a building having an elevator shaft, a movable floor section set within the shaft; a counter-weight frame movably mounted below the floor section; means between the counter-weight frame and the floor section for raising the latter to its normal position; mechanism for locking the floor section in normal position with its surface flush with the flooring; means for tripping the locking mechanism whereby the floor section may be depressed; and means for moving the counter-weight frame and floor section so as to clear the shaft.
10. In combination with the flooring of a building having an elevator shaft; a movable floor section set within the shaft; a counter-weight frame beneath the floor section; connections between the frame and floor section for holding the latter in normal position; means between the floor section and counter-weight frame for guiding the one on the other; locking mechanism for holding the floor section in normal position with its surface flush with the flooring; and means for tripping the locking mechanism so that the floor section may be depressed to make way for the passage of an elevator.
11. In combination with the flooring of a building having a shaft, a movable floor section set within said shaft; mechanism for locking the floor section with its surface flush with the surface of the flooring; a counter-weight frame; means whereby the floor section and counter-weight frame may be moved relatively; locking means for locking the floor section to the counter-weight frame; an elevator operating above the floor section; and means carried by the elevator for tripping both the locking mechanism and the locking means whereby the floor section may be depressed and also unlocked from the counter-weight frame.
12. In combination, a depressible plat-

- form; counterbalancing means for holding said platform flush with the flooring; mechanism for locking the platform in its normal flush position; an elevator operating upon the platform; and means carried by the elevator for tripping the locking mechanism so that the elevator may depress the platform.
13. In combination with a depressible platform, mechanism for locking the same in a normal position; means whereby the platform may be locked depressed; an elevator working above the platform; and means carried by the elevator whereby, as the latter is lowered, the locking mechanism of the platform may be tripped so that the platform may be depressed and the locking means may be actuated to lock the platform in depressed position.
14. In combination with a flooring used for traffic, a depressible platform working in the flooring capable of sustaining such traffic and movable to a limited extent to a position just below said flooring; a plurality of spring controlled bolts carried by the platform for locking the same to the flooring with the two surfaces flush; an elevator working above the platform; means carried by the elevator and adapted to extend through the platform whereby to trip the bolts as the elevator is lowered so that the latter may depress the platform to the extent stated.
15. In combination with the flooring of a building having an elevator shaft therein, a counter-weight frame movably mounted below the flooring and surrounding the shaft; a floor section set within the shaft; counter-weight mechanism between the frame and floor section for holding the latter normally in the shaft; locking mechanism for locking the floor section in the shaft with its surface flush with the surface of the flooring; locking means carried by the counter-weight frame for locking the latter and the floor section together; an elevator operating above the floor section; tripping means carried by the elevator for tripping the locking mechanism; and a shiftable tripping means carried by the elevator for tripping the locking means, whereby, when the locking mechanism is tripped, the floor section may be depressed, and, when the locking means is tripped, the floor section and counter-

weight frame may be unlocked together and shifted laterally, if desired.

16. In combination with a depressible platform, mechanism for locking the same in a normal position; means whereby the platform may be shifted laterally; means whereby the platform may be locked in a predetermined position before being shifted laterally; an elevator working above the platform; and means carried by the elevator whereby, as the latter is lowered, the locking mechanism of the platform may be tripped so that the platform may be depressed and the locking means may be actuated to lock the platform in depressed position preparatory to being shifted laterally.

17. In combination with a depressible platform, mechanism for locking the same in a normal position; means whereby the platform may be depressed to a limited extent or to a position just below its normal surroundings; means whereby the platform may be locked in depressed position; and means for shifting the platform laterally while in depressed position.

18. In combination with a depressible platform, mechanism for locking the same in normal position; means for tripping the locking mechanism so that the platform may be depressed; means for shifting the platform laterally after it has been depressed; said means being capable of returning the platform to a position where it may be raised to its normal position; and means whereby the platform may be raised to its normal position and locked therein.

19. In combination with a depressible floor section and mechanism for locking the same in normal position; an elevator working above said depressible floor section and having means for tripping the locking mechanism so that it may depress the floor section; means for locking the floor section upon reaching a predetermined level; means for shifting the floor section laterally at such level whereby the elevator is enabled to pass the same and descend through the shaft; and means carried by the elevator for tripping the locking means whereby the floor section may be returned to normal position.

WILLIAM J. MORRIN.
